Application March 28, 1933. Serial No. 663,144

3 Claims. (Cl. 200—111)

This invention relates to a switch or similar means for initiating an X-ray exposure by arcing a current between electrical contacts. The contacts in their normal position are so shaped and spaced that the current cannot normally jump between them. When the relationship of the contacts are changed, by a means forming the subject matter of this invention, the current will arc over or bridge the gap and initiate the X-ray exposure at the desired moment.

The object of this invention is to provide a simple high tension switching device operative to change the sphericity of a normally spherical contact, whereby the tendency of the current to jump or arc from said altered contact to a spaced companion contact is increased, and the spark resultantly occurs at the desired time.

More specifically, the apparatus comprises a pair of definitely spaced spherical members or contacts so positioned with respect to one another that a spark will not jump between them normally. Movable through one of these contacts is a slender stem in the form of a rod or wire, which is by a suitable mechanism, thrust out of the sphere normally enclosing it, toward the other sphere. This action, tending to momentarily destroy the sphericity of the sphere in which the stem is moved, causes the gap to be jumped by the current.

While I have herein described my improved device for use in connection with an X-ray system, it will be understood that the same has other uses, such as for a high-tension switch or the like.

In the accompanying drawing Fig. 1 diagrammatically illustrates the device as used in an X-ray system, and Fig. 2 is a longitudinal sectional view through the switch means.

In Fig. 1 of the drawing, the usual high tension generator used in X-ray systems is shown. It comprises the high tension transformer 1, connected in the customary manner to the valve 2. A filament transformer 3 connects to the filament of the valve, and another filament transformer 4 connects to the filament of the X-ray tube 5. The anode 6 of the X-ray tube 5 is connected to a spherical contact member 7 spaced by a fixed gap 8 from a similar spherical contact 9. The sphere 9 connects to the several transformers 1, 3 and 4 in the manner shown and also to the condensers 10.

Movable within the sphere 9 is a stem in the form of a rod or wire 11 adapted to have its end projected out of the sphere into the gap 8 and toward the other sphere 7. The stem 11 is of

metal and in electrical contact with the sphere 9. It is moved through a guide 12 located within the sphere. The stem 11 is secured to the end of a rod 13 of fibre or other insulating material, said rod 13 being slidable through a guide 14 projecting from the outside of the sphere 9. The guide 14 is surrounded by a tube 15 of insulation, which is provided at a distance from the sphere 9 with a solenoid 16. At its lower end, the rod 13 is secured to an iron plunger 17, adapted to be drawn upwardly when the solenoid is energized. A stem 18 on the plunger 17 is guided by an opening in the bottom 19 of the tube 15, during movement of the plunger 19 and the rods 13 and 11 carried by it.

From the foregoing, the operation of the device will be readily understood. The current normally will not jump the gap 8 between the two spheres 7 and 9, it being well understood that a gap between spherical contacts is not readily jumped. To cause a spark to jump between the spheres 7 and 9, it is merely necessary to close the switch 20 connecting the solenoid with a source of current, whereupon the solenoid, being energized, will draw the plunger 17 upwardly, thrusting the stem 11 out of the body of the sphere 9 and into the gap 8 and toward the other sphere 7. The outward movement of the stem 11 is limited by a spring 21 surrounding the stem and which contacts with the guide 12. The extent of the projection of the stem 11 out of the sphere 9 is determined by the purpose to which the device is put. When used in an X-ray apparatus, where it is desired to have a spark jump the gap between the two spheres, the stem need extend only partly across the gap toward the other sphere. If the device is used as a high tension switch, the stem may be projected from the switch within which it is located, across the gap and into actual contact with the other sphere.

In using the term "sphere" herein, I intend that it shall refer to any generally spherical member or other member so shaped as to by its shape act to decrease the tendency of the current to jump the gap. The stem 11 movable out of one of the spheres into the gap between the spheres acts to destroy the sphericity of the sphere out of which it moves, thus aiding the current to arc or spark across the gap. The use of spherical members on the opposite sides of the spark gap prevents voltage losses and generally increases the efficiency of the apparatus.

Having described my invention, what I claim is:

1. A device of the character described comprising, spaced spheres carrying current and separated to such an extent as to normally prevent arcing of the current between them, a stem normally held in a retarded position within one of the spheres, said stem being secured to an insulated rod having a portion projecting outside 10 of the sphere, a tubular casing secured to and projecting from the sphere, said casing surrounding that portion of the rod which protrudes from the sphere, a solenoid surrounding the casing, and an armature attached to the rod within the 15 casing so that when the solenoid is energized the stem carried by the rod is projected out of the sphere toward the other sphere.
2. A device of the character described comprising, spaced spheres defining a spark gap between them, a stem normally held in a retarded 20 position in one of said spheres, said stem having a portion projecting outside of the sphere and carrying an armature, and a solenoid mounted

outside of the sphere for moving the armature and stem carried thereby to shift a portion of the stem out of the sphere when the solenoid is energized.

3. A device of the character described comprising, spaced spheres carrying current and separated to such an extent as to normally prevent arcing of the current between them, a stem normally held in a retarded position within one of the spheres, said stem protruding from the end of a rod of insulation, the rod having a portion protruding from the sphere, a tubular insulated casing secured to and projecting from the sphere, said casing surrounding that portion of the rod which protrudes from the sphere, a solenoid surrounding and supported by the casing, and an armature secured to one end of the rod within the casing, and means in the casing for guiding the rod and armature in its movement therein.

HARRY D. GARRETSON.
